UNITED STATES PATENT OFFICE.

CHARLES H. SIMMONS, OF CHICAGO, ILLINOIS, ASSIGNOR TO MILTON E. PAGE, JR., ADOLPH T. JOHANSON, AND CHRISTOPHER M. PAGE, ALL OF CHICAGO, ILLINOIS, TRUSTEES FOR AABALL MANUFACTURING COMPANY, A COMMON-LAW TRUST.

OIL BURNER.

Application filed January 25, 1923. Serial No. 614,749.

To all whom it may concern:

Be it known that I, CHARLES H. SIMMONS, a citizen of the United States, and resident of Chicago, in the county of Cook and State 5 of Illinois, have invented certain new and useful Improvements in Oil Burners, of which the following is a specification.

My invention relates to burners, and relates more particularly to those using liquid 10 fuel, such as oil, in which the latter is subdivided or carburetted under the action of centrifugal force.

One object of the invention is the employment of an electric-driven motor which 15 may be operated at moderate speed, and hence may be produced or manufactured relatively economically, a further aim of the invention being to lubricate the gearing employed by the oil later used in and consumed at the burner, and to this end the 20 gears may be submerged in the supply of such oil.

To the accomplishment of these and other 25 desirable ends, I have provided the preferred embodiment of the invention presented in detail in the accompanying drawings forming a part of this specification and throughout the several views of which like 30 reference characters have been used for the same parts.

In these drawings,—

Fig. 1 is a partial elevation and partial 35 central longitudinal section through the improved burner showing it in place in the lower portion of a furnace;

Fig. 2 is an enlarged partial elevation and partial section on line 2—2 of Fig. 5, showing the screw pump mechanism for feeding the oil;

Fig. 3 is a horizontal section on line 3—3 of Fig. 1;

Fig. 4 is a horizontal section on line 4—4 of Fig. 1; and

Fig. 5 is a plan view and partial section 45 of the portion of the structure shown in Fig. 2, but on a reduced scale.

By reference to the drawings, it will be seen that the improved and novel appliance 50 includes a base 11, a portion of which is intended to be positioned inside of the lower portion of the furnace 12, the other part of the base projecting forwardly out of the

furnace so that the electric motor 13 which it carries will be removed sufficiently from the source of heat inside of the furnace. 55

That part of the base in the lower portion of the furnace has a compartment 14 formed by suitable upstanding walls 15, 15 and a cover-plate 16.

Such compartment or chamber is connected to a suitable source of liquid fuel supply, such as oil, not shown, by a pipe 17 which projects inside of the chamber and is equipped internally of such chamber with a suitable valve structure 18 through which 60 the oil is delivered into the compartment and which is operated by an arm 19 on a lever 21 fulcrumed at 22 on one wall of the chamber, such lever at its other end carrying a float 23 whereby the oil or other liquid 65 in the compartment is automatically maintained at a substantially predetermined level.

An upright skeleton standard or frame 24 mounted on the floor or bottom wall of the 70 compartment has roller bearings 25 and 26 for a revoluble, vertically-disposed, hollow shaft 27 which extends upwardly out through a hole in the cover plate.

The open lower end of such hollow shaft 80 is fitted with a screw pump element 28 secured to the shaft internally at such end and projecting down beyond the bottom of the shaft nearly to the base of the compartment. 85

As is shown most clearly in Fig. 2, such screw or spirally-formed member is enclosed in a cylindrical shell 29 reaching from the bottom wall of the compartment, to which it is secured in any approved manner, to the under face of that cross part 31 of the standard fitted with the lower roller-bearing 26, the bottom portion of the shell having a number of apertures 32 therethrough to permit the oil to flow into its 90 interior.

The hollow shaft 27 is equipped with a spiral-gear 33 driven by another spiral-gear 34 on a suitably-journalized, horizontal shaft 35 extended forwardly out through the 100 front wall of the compartment and joined to the motor-shaft by a flexible coupling 36 of any appropriate or suitable design.

It will be observed that the height of the

oil in the compartment is such that these intermeshing, co-operating gears 33 and 34 are immersed therein and lubricated thereby, such body of oil flowing gradually into 5 the shell 29, where it comes under the influence and action of the screw-pump 28.

At its upper end, the hollow shaft carries a round, hollow, flaring burner or oil carbureting or atomizing member 37, the hub 10 38 thereof at its lower end being secured to the shaft by a set-screw 39, the shaft projecting up through a central hole in the bottom of member 37.

This part 37 is of general pail-shape, its 15 floor or bottom wall having apertures 41 for the admission of air to its interior.

The pipe inside of the element 37 has a number of spirally-arranged, oil-delivery holes 42 which may be opened or closed 20 more or less by an adjustable collar or sleeve 43 held on the shaft in adjusted position by a set-screw 44.

A plug 45 fits in the open top end of the shaft and carries a horizontal, circular plate 25 46 with a beveled edge, spaced vertically above the similarly beveled top edge of the member 37 to provide a circular slit or opening through which the mixed oil and air are discharged under the action of centrifugal force ready for combustion, the additional oxygen for which is supplied by the surrounding air.

In order to admit air to the oil compartment 14 to facilitate the pumping of the oil to the rapidly-rotating distributor 37, its cover is supplied with one or more vent holes 47.

A circular support 48 of suitable shape 40 spaced away from and surrounding the burner element 37 carries an inclined refractory wall 49 sloping downwardly inwardly toward the burner, the appliance being fitted with a pair of appropriate pilot lights or burners 51 and 52.

The structure operates practically as follows:

The motor, removed or positioned away from the hot zone, rotates at a moderate speed, for example, 1750 R. P. M., and 50 through the gears 34, 33, it revolves the burner at high speed.

The oil in the bottom of the compartment or chamber flows into the shell through the apertures of the latter and is pumped up 55 the hollow shaft by the screw or spiral member 28, being discharged laterally therefrom by centrifugal force through the shaft ports 42, where it becomes mixed with air entering the apertures 41, the mixture being delivered through the circular opening between the parts 37 and 46, and being consumed in a whirling flame after such exit.

Any excess of oil or any delivery thereof when the pilot lights are not burning by 60 accident, flows down the wall 49 and returns

to the oil compartment through the holes in its top wall.

It will be perceived that although the burner is rotated at a relatively high speed, the motor which does the work revolves at 70 a much slower speed, the increase in speed being due to intervening gearing properly lubricated by reason of its immersion in the oil supply, the oil from the latter being gradually drawn off for combustion purposes.

The invention is not limited and restricted to the precise and exact details of structure herein presented, but it is susceptible of a 80 variety of satisfactory embodiments, all differing more or less in mechanical details, but all incorporating the main or fundamental principles constituting the essence of the present invention as defined by the appended claims.

I claim:

1. In a liquid fuel burner construction, the combination of a compartment, means to admit liquid fuel thereto, a substantially vertical hollow revoluble shaft projecting into said compartment and adapted to receive fuel therefrom, a fuel burner mounted on and adapted to receive its fuel from the passage in said shaft, a substantially horizontal drive shaft extended through a wall of said compartment into the interior thereof, gearing submerged in the fuel in said compartment between and operatively connecting said horizontal and vertical shafts, and an electric motor outside of said compartment to revolve said horizontal shaft.

2. In a liquid fuel burner construction, the combination of a liquid fuel compartment, a rotatable hollow shaft projecting into said compartment and receiving its fuel therefrom, a burner fixed to and revoluble with said shaft and receiving its fuel from the passage in the latter, gearing submerged in the fuel in said compartment and lubricated thereby, means to operate said gearing, and a screw-pump to force the liquid from said compartment into said shaft.

3. In a liquid fuel burner construction, the combination of a liquid fuel compartment, a rotatable hollow shaft projecting into said compartment and receiving its fuel therefrom, a burner fixed to and revoluble with said shaft and receiving its fuel from the passage in the latter, gearing submerged in the fuel in said compartment and lubricated thereby, means to operate said gearing, an apertured shell below the lower end of said shaft and a screw-pump member revoluble with said shaft and located at least in part in said shell to feed the fuel from the compartment into said shaft and burner.

In witness whereof I have hereunto set my hand and seal.

CHARLES H. SIMMONS. [L. S.]
